UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF FORMING A FORGED FULCRUM.

1,335,808.

Specification of Letters Patent.

Patented Apr. 6, 1920.

Application filed April 26, 1918. Serial No. 230,988.

To all whom it may concern:

Be it known that I, LOREN L. WHITNEY, a citizen of the United States, and resident of Hammond, in the county of Lake and State of Indiana, have invented certain new and useful Improvements in Methods of Forming a Forged Fulcrum, of which the following is a specification.

This invention relates to a one-piece forged fulcrum.

The object of the invention is to simplify and improve the method for making a one piece forged fulcrum.

Generally speaking, this and other objects are accomplished by making a forged fulcrum employing the method consisting first in providing a single blank, then pressing an opening therein for the reception of a brake lever and forming portions for co-operation with the tension and compression members of a brake beam.

The invention is illustrated on the accompanying sheets of drawings, in which:

Figure 1 is a side elevation, and Fig. 2 an end view of the blank from which the fulcrum is made;

Fig. 3 is a plan view, and Fig. 4 a side elevation of the blank blocked preparatory to finishing the forged operation;

Fig. 5 is a plan view, and Fig. 6 a side elevation of the forged fulcrum, the lever opening, compression band member and tension rod seat having been completed, the flashings not having been removed;

Fig. 7 is a plan view, and Fig. 8 a side elevation of the fulcrum with the flashings removed;

Fig. 9 is a plan view, and Fig. 10 a side elevation of the completed forged fulcrum after the intermediate portion has been twisted 40° with respect to the ends of the fulcrum.

Fig. 11 is an end view of the completed fulcrum.

Fig. 12 is a detail sectional view of the compression member end of the fulcrum showing a notch in the rear wall for the reception of a projection on the compression member.

The second sheet of drawings discloses a modification of my method, in which—

Fig. 13 is a side elevation, and Fig. 14 an end view of a single piece of stock;

Fig. 15 is a plan view, and Fig. 16 a side elevation of the piece of stock after it has

received its first forming operation, including a displacement of metal at the center and at one end of the blank, the ends of the blanks being formed at an angle of 40° with the body portion of the fulcrum;

Fig. 17 is a plan view, and Fig. 18 a side elevation of the fulcrum after the lever opening and compression and tension co-operating members are formed, the flashings not having been removed;

Fig. 19 is a plan view, and Fig. 20 is a side elevation of the fulcrum with the flashings removed;

Fig. 21 is a plan view, and Fig. 22 a side elevation of the completed fulcrum;

Fig. 23 is a fragmentary plan view, and Fig. 24 a fragmentary side elevation of a fulcrum, the compression member end of which is formed differently from the arrangement shown in the other figures of the drawing.

The various novel features of my invention will be apparent from the following description and drawings and will be particularly pointed out in the appended claims.

Referring first to Figs. 1 and 2 of the drawings, it will be noted that I have provided a single blank 25 in the form of a rectangular prism, which preferably is considerably deeper than it is wide. In the first forming operation, the dies are pressed into the narrow sides of the blank to form opposite depressions 26 at the middle of the fulcrum blank, and a depression 27 at the compression member end thereof, as shown in Figs. 3 and 4. In the next forming operation the central opening 26 is practically made complete with the exception of the central flashing 28, and at the same time the compression end is formed into a band 29 for the reception of the brake beam compression member, and the other end of the fulcrum is provided with a tension rod seat 30, as shown in Figs. 5 and 6. At the same time the walls of the central lever opening of the fulcrum are provided with bearing hubs 30a. In the next operation, the flashings are trimmed from the fulcrum, as shown in Figs. 7 and 8. In the next operation the central body portion of the fulcrum is twisted 40° with respect to the ends of the fulcrum, and the walls 31 and 32 of the lever opening are provided with holes 33 for the pivot pin of the brake lever, as shown in Figs. 9 and 10. The rear wall of the band

29 is provided with a notch 34 to receive a projection on the brake beam compression member. By means of this simple method a one piece forged fulcrum may be formed 5 which is adapted to meet the various requirements for successful commercial operation.

By referring to the other sheet of drawings, it will be noted that the same blank 10 is shown in Figs. 13 and 14. However, as shown in Figs. 15 and 16, it will be noted that the ends 35 and 36 of the blank are first forged vertically and angularly with respect to the central body portion of the 15 fulcrum instead of twisting the body portion, as shown in Figs. 9 and 10. Also the metal in the central body portion is displaced to form depressions 37, a depression 38 also being formed in the compression 20 member end of the fulcrum. In the next step the fulcrum is provided with a band 39 for receiving the brake beam compression member and provided with a seat 40 for the brake beam tension member, the lever 25 opening 41 also being completed with the exception that the flashings are still present. The next step includes the trimming of the flashings away from the fulcrum, as shown in Figs. 19 and 20, and the final step includes the drilling or punching of holes 42 30 for the pivot pin of the brake lever.

If it is desired, the compression member end of the fulcrum may be in the form of laterally extending projections 43, (Figs. 23 35 and 24) which may be riveted to the compression member instead of providing a band, as shown in the other forms of fulcrums.

It is apparent that there may be other 40 modifications of the invention, and it is my intention to cover all such modifications which do not involve a departure from the spirit and scope of the invention as set forth in the following claims.

45 I claim:

1. The method of forming a forged fulcrum consisting first in providing a single blank, then pressing an opening therein for the reception of a brake lever, and forming 50 portions for coöperation with the tension and compression members of a brake beam.

2. The method of forming a forged fulcrum consisting first in providing a single blank, then forming an opening intermediate its ends for the reception of a brake lever, and then forming a tension member seat and a portion to coöperate with a brake beam compression member. 55

3. The method of forming a forged fulcrum consisting first in providing a single blank, then providing said blank with an opening intermediate its ends for the reception of a brake lever, and then forming a band at one end for the reception of a compression member and a seat in the other end thereof for a tension member. 60

4. The method of forming a forged fulcrum consisting first in providing a single blank, then forming an opening intermediate its ends for a brake lever, then forming a band at one end thereof for a brake beam compression member and a seat at the other end for a tension member, and then 65 relatively twisting an intermediate part of the fulcrum with respect to the ends thereof. 70

5. The method of forming a forged brake beam fulcrum consisting first in providing a single blank, then forging the ends thereof at an angle with respect to an intermediate portion of the blank, then forming an opening in the middle portion of the blank 80 for the reception of a brake lever and forming the ends to coöperate with brake beam compression and tension members.

6. The method of forming a forged brake beam fulcrum consisting first in providing a single blank, then forging the ends thereof at an angle with respect to an intermediate portion of the blank, then forming an opening in the middle portion of the blank for 85 the reception of a brake lever and forming the ends to coöperate with brake beam compression and tension members, and then forming openings in the middle portion of the fulcrum for the reception of a brake 90 lever pivot member. 95

Signed at Hammond, Indiana, this 23rd day of April, 1918.

LOREN L. WHITNEY.
